UNITED STATES PATENT OFFICE.

HERMAN E. ROYS, OF NEW YORK, N. Y., ASSIGNOR, BY MESNE ASSIGNMENTS, TO
CAMEOSCOPE CORPORATION, A CORPORATION OF NEW YORK.

DESIGN FOR A CASING FOR MOVING-PICTURE MACHINES.

47,410.

Specification for Design.

Patented June 1, 1915.

Application filed October 31, 1914. Serial No. 869,704. Term of patent 3½ years.

To all whom it may concern:

Be it known that I, HERMAN E. ROYS, a citizen of the United States, residing in the city of New York, borough of Manhattan, in the county and State of New York, have invented a new, original, and ornamental Design for a Casing for Moving-Picture Machines, of which the following is a specification, reference being had to the accompanying drawings, forming part thereof.

Figure 1 is a side view of a moving-picture machine showing my new design, and Fig. 2 is a corresponding front elevation.

I claim:

The ornamental design for a casing for a moving-picture machine, as shown.

HERMAN E. ROYS.
